UNITED STATES PATENT OFFICE.

CHRISTIAN WILLIAM MEINECKE, OF JERSEY CITY, NEW JERSEY.

DESIGN FOR A NIPPLE FOR NURSING-BOTTLES, &c.

SPECIFICATION forming part of Design No. 30,761, dated May 16, 1899.

Application filed March 30, 1899. Serial No. 711,163. Term of patent 14 years.

To all whom it may concern:

Be it known that I, CHRISTIAN WILLIAM MEINECKE, a citizen of the United States, residing at Jersey City, in the county of Hudson and State of New Jersey, have invented and produced a new and original Design for a Nipple, of which the following is a specification.

The design consists in a nipple for nursing-bottle fittings or tubes and for nipple-shields having a spherical head or mouth and surmounting a cylindrical neck which rises from a bead.

The design is illustrated in the annexed drawings, in which—

Figure 1 is a sectional view of the nipple. Fig. 2 is a plan view of Fig. 1. Fig. 3 is a perspective view of the nipple made according to my design.

The leading feature of my design consists in a spherical head or mouth surmounting a cylindrical neck, which latter rises from a rounded bead formed at the base or open end of the said cylindrical portion.

Referring to the drawings, the reference-numeral 1 designates a rounded bead which surrounds the lower open end of a cylindrical neck portion 2, which latter is slightly smaller in diameter than the greatest diameter of the bead 1. The said cylindrical neck is surmounted by a spherical or globular head or mouthpiece 4, which latter is of greater diameter than the cylindrical neck 2, and the extreme outer end of said spherical head is provided with several apertures or perforations 5, all as clearly shown in the drawings.

What I claim as new, and desire to secure by Letters Patent, is—

The design for a nipple for nursing-bottle fittings and nipple-shields as herein shown and described.

In testimony whereof I have hereunto set my hand in the presence of two subscribing witnesses.

CHRISTIAN WILLIAM MEINECKE.
